UNITED STATES PATENT OFFICE.

WILLIAM WOLFE, OF BATAVIA, OHIO.

HEEL-BUILDING MACHINE.

SPECIFICATION forming part of Letters Patent No. 760,768, dated May 24, 1904.

Application filed August 25, 1903. Serial No. 170,745. (No model.)

REISSUED

To all whom it may concern:

Be it known that I, WILLIAM WOLFE, a citizen of the United States, residing at Batavia, in the county of Clermont and State of Ohio, have invented a new and useful Heel-Building Machine, of which the following is a specification.

This invention relates to improvements in machines of that class employed in the manufacture of heel-blanks, and has for its principal object to provide means for properly adjusting a number of assembled taps or lifts and unite the same by a simple fastening means in the form of a heel-blank.

A further object of the invention is to provide novel mechanism of the single-actuating-movement type, wherein the parts assume inoperative position immediately after each operative movement and remain in inoperative position until again connected to the actuating mechanism.

With these and other objects in view the invention consists in the novel construction and arrangement of parts hereinafter described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a side elevation of the heel-building machine constructed in accordance with the invention. Fig. 2 is a front elevation of the same. Fig. 3 is a plan view, partly in section, on the line 3-3 of Fig. 1. Fig. 4 is a detail perspective view of one of the tap or lift adjusting blocks. Fig. 5 is a transverse sectional elevation of a slightly-modified construction of nail-block. Fig. 6 is a detail view of a portion of the mechanism for imparting intermittent rotative movement to the nail-feeding disk. Fig. 7 is a plan view of a portion of the nail-feeding disk.

Similar numerals of reference are employed to indicate corresponding parts throughout the several figures of the drawings.

The frame 1 of the machine is mounted on 50 a suitable bed or table at a convenient height above the floor, and includes a base member 2 and a vertical arm 3. The base is provided with a pair of horizontally-disposed guides 4 for the reception of a slide 5, by which the 55 assembled taps or lifts are moved to position under the nail-driving mechanism, said slide being provided near one end with a gage 6, against which the lifts are piled until they are level with the top of the gage. The slide 60 is connected by a helical spring 7 to a bell-crank lever 8, pivotally mounted on a stud at one side of the spindle 3 and receiving motion in the manner hereinafter described.

At opposite sides of the base-plate are arranged blocks 9, 10, and 11. These blocks serve as supports for a plurality of adjustable plates 12, each of which is provided with a slot 13 for the passage of a locking-bolt 14, adapted to a threaded opening in the block, 70 and said plates are adjustable and independent of each other and all are clamped in an adjustable position by means of the bolts. The position assumed by the plates is of course dependent on the shape of the heel to be made, 75 and these plates are preferably each of a thickness about equal to that of one of the taps or lifts, so that each will engage its proper tap or lift and move the whole to a predetermined position with respect to the remaining portion 80 of the heel. The plates carried by the blocks 9 and 10 extend in a direction transverse of the base and are arranged directly opposite each other, while the plates carried by the block 11 are slightly curved, in order that their 85 operating faces or ends may engage the rear face of the heel, the mounting of these plates being such as not to interfere with free movement of the blank-carrying slide 5.

At one side of the base is a vertically-disposed rod 15, carrying a perforated nail-block 16, that may be adjusted to a position immediately above the several tap or lift engaging plates and locked in such position by means of a set-screw 17, and said block may be adjusted vertically in accordance with the height of the heels to be made. This block is provided with an approximately central opening

18, through which nails are fed singly from the chute 19, the nails being held from falling through the opening by means of a small strip or plate 19^a, preferably arranged in a slot at the bottom of the block. This plate is rearwardly extended and has a terminal hook 20, connecting the bell-crank lever 8, so that when the lever is moved the slide will be withdrawn from under the nail and the latter allowed to fall into contact with the heel-blank.

The frame of the machine is provided with an upwardly-projected arm 22, in which is formed a guiding-opening for the reception 15 of a vertically-movable bar 23. The lower end of this bar is threaded for the reception of a screw 24, that is provided with a milled collar 25, that may be turned in order to adjust the position of the screw, and to the lower 20 end of the screw is secured a chuck 26, carrying a driver-rod 27, which is reciprocated in order to drive the nails through the nail-block to the heel-blank.

The frame of the machine is provided with 25 bearings for the reception of a shaft 30, to the inner end of which is secured a combined cam and crank disk 31, having a wrist-pin 32, that extends through a horizontally-disposed slot 33 in a cross-head carried by or forming 30 a part of the bar 23, the length of the slot being at least equal to the throw of the crank-pin. This mechanism serves to impart driving movement to the driver-rod.

On that side of the crank-disk opposite the 35 wrist-pin is a lug or roller 34, that is adapted to make contact with a vertically-movable cam-bar 35, guided in a cross-bar 36 at the top of the frame, the bar being held in position by a headed pin or screw extending 40 through a vertical slot in said bar.

At the top of the frame is a rearwardly-extending arm 38, carrying a vertical stud 39, that forms the center of rotation of a nail-feeding disk 40. This disk is provided with 45 an annular series of nail-receiving pockets 41, to which nails are successively supplied in any suitable manner, and these pockets are successively brought into vertical alinement with the upper end of the nail-chute 19, so that 50 single nails may fall through the chute to the opening 18 of the nail-block, preliminary discharge of the nails being prevented by contact with the arm or a suitable guard 41' on which the nails rest up to the time the chute 55 is reached. The disk is provided with a number of cam-teeth 43, corresponding to the number of pockets, and with these teeth engages the cam-bar 35, the bar being moved upward once at each operation of the machine and 60 serving to impart angular movement to the disk to the extent of a single tooth.

At the upper end of the cam-bar 35 is a cam 45, that serves to engage the cam-teeth 43 at each upward movement of the cam-bar, and

at each operation an angular movement is 65 imparted to the disk to an extent equal to the distance between two of the cam-teeth, so that the nail-receiving pockets are successively presented in alinement with the nail-chute. The limit of effective movement of this cam is 70 fixed by a guard 46, arranged at the upper end of the cam-bar, and in operation the upward movement of the cam-bar serves to impart to the disk a movement sufficient to feed a single nail to the chute at each operation. 75 The guard member is provided with a slot 47, through which extends a locking-screw 48 for locking the guard in any position to which it may be adjusted.

The combined crank and cam-disk has an 80 irregular periphery, with which engages a roller 49, arranged at the inner end of a bell-crank lever 50, that is pivoted to an arm or bracket 51, extending rearwardly from the standard 3. The opposite arm of the bell-crank lever is connected by a link 52 to the lever 8 and the two levers are so proportioned that when operated upon by the cam-surface of the disk movement will be imparted to the slide 5 and force the same in the direction of 90 the heel-shaping plates 12, the connecting-spring between the lever 8 and the slide being such as to yieldably hold the rear edges of the heel-forming taps or lifts against the rear adjusting-plates and thus properly position 95 the several lifts, while at the proper time the plate 14 will be withdrawn and allow the entering end of the nail to rest against the uppermost tap or lift in position to be driven home by the rod 24. This operation of the 100 mechanism may be somewhat modified, as shown in Fig. 5, wherein the nail-block slide 14' is shown in the form of a rod or plate having a tapering end portion against which the pointed end of the nail rests, the relation between the rod or plate and the nail being such that when downward movement is imparted to the nail by the driver-rod the nail will be forced past the plate and into the heel-blank. 105

On the shaft 30 is arranged a clutch, which 110 may be of any ordinary construction and which forms no part of the present invention, the clutch-operating mechanism being connected to a suitable pedal-lever 60 and being preferably arranged in such manner that a single 115 portion of the pedal-lever will impart a single rotative movement to the shaft.

In the operation of the mechanism the lifts or blanks are assembled on the slide 5 to a height determined by the gage 6, and on the connection of the shaft to the actuating mechanism the slide is drawn inward or in the direction of the nailing mechanism until the taps or lifts engage the adjusting or shaping plates and the lifts are moved to proper position. The slide 19^a is then withdrawn, allowing a previously-fed nail to descend until its entering end rests on the uppermost lift. 125

The driving-rod is now forced down until the nail has been driven through the lifts and the blank is ready for subsequent treatment.

Having thus described the invention, what is claimed is—

1. In a heel-building machine, a plurality of sectional and independently-adjustable shaping-blocks for engagement with the sides and rear face of the heels, and a slide for receiving and moving heel-blanks into engagement with said blocks.
2. In a heel-building machine, a plurality of independently-adjustable shaping-blocks, a slide for supporting the taps or lifts, and a gage carried by the slide and serving in connection with the latter to force the taps or lifts into engagement with the shaping-blocks.
3. In a heel-building machine, a plurality of independently-adjustable shaping-blocks, a slide for the reception of the taps or lifts, a gage carried by the slide and serving in connection with the blocks to shape the heel-blank, and a yieldable means for moving said slide in the direction of the blocks.
4. In a heel-building machine, a bed-plate having guides, a slide adapted to said guides, a pair of sectional and independently-adjustable shaping-blocks carried by the bed-plate and extending over the slide, a third shaping-block carried by the bed-plate and held in position for engagement with the rear face of

the heel-blank, and means for moving the slide to force the taps or lifts into engagement with the several shaping-blocks.

5. In mechanism of the class described, shaping devices, a perforated nail-block for engaging the top of the blank, means for feeding nails to the perforations, a nail-rod, a bar carrying the same, a cam-disk having a wrist-pin connected to the bar, and levers for transmitting the cam movement to the blank-supporting slide.

6. In mechanism of the class described, shaping devices, a blank-supporting slide, a perforated nail-block, means for feeding nails to the perforation, a nail-rod, a bar carrying the same, a cam-disk having a wrist-pin connected to the bar, a plurality of connected bell-crank levers carried by the frame of the machine, a pin or roller mounted at one end of one of the bars and connecting the cam-disk, and a spring connecting the opposite end of the system of levers to the slide, substantially as specified.

In testimony that I claim the foregoing as my own I have hereto affixed my signature in the presence of two witnesses.

WILLIAM WOLFE.
